UNITED STATES PATENT OFFICE.

OWEN D. MCFARLAND, OF CHICAGO, ILLINOIS, ASSIGNOR TO THE GUYTON & CUMFER MANUFACTURING COMPANY, OF CHICAGO, ILLINOIS, A CORPORATION OF ILLINOIS.

ROOFING MACHINE.

Application filed February 2, 1921. Serial No. 441,723.

To all whom it may concern:

Be it known that I, OWEN D. MCFARLAND, a citizen of the United States, residing in Chicago, county of Cook, and State 5 of Illinois, have invented certain new and useful Improvements in Roofing Machines, of which the following is a specification.

This invention relates to improvements in roofing machines and relates more particularly to an embossing or print apparatus which is adapted to be interposed in any type of paper or roofing machine by merely removing two of the cooling rolls and inserting this printing or embossing apparatus.

Among its salient objects is to provide an apparatus having adjustable bearings by means of which the pressure roll may be positioned to contact the embossing roll at 20 any desired pressure with a quick release attachment for automatically withdrawing the pressure roll without disturbing the pressure adjustments; to provide an apparatus in which the pressure and embossing rolls are geared in timed relation whereby the roofing or paper stock to be printed or embossed is fed uniformly through the embossing stage and due to the fact that there is an excess of material maintained in a loop just prior to the stock being fed to the embossing roll the print or embossing is regular and distinct; to provide an apparatus in which the pressure roll is kept clean and prevented from gumming and sticking to the material treated by constantly scraping its surface and applying water or a light cleansing substance to the surface of the roll; to provide an apparatus having a series of rolls equipped 35 with guide flanges so arranged that the sheet is accurately directed between the embossing or printing rolls; to provide an apparatus which is compact and one which accomplishes the printing and embossing of 40 the material in a manner superior to that obtained by similar machines heretofore in common use.

In the drawings—

Fig. 1 is a side elevation of the apparatus 50 with parts broken away;

Fig. 2 is an end of the apparatus shown in Fig. 1 with parts broken away and parts omitted for more clearly designating the details of the machine;

Fig. 3 is a diagrammatic view, showing

a series of coolers with the arrangement of the embossing machine positioned therein;

Fig. 4 is a plan view of a section of a roof on which the printed or embossed material has been used.

Referring to the drawings—the roofing material 1, such as a common type of felted or fibrous materials common in the roofing art in the manufacture of prepared roofing, is threaded to the machine over the roll 2 65 which is geared to a similar guide roll 3 positioned directly below it. These rolls are supported on shafts 4 and 5 mounted in suitable bearings on the frame 6. The roofing material, after passing over the upper 70 roll, is directed between the rolls from whence it drops into a loop, as shown at 1^a. This loop furnishes an excess of material so that the roofing, as it passes through the embossing rolls, will not be stretched and 75 pulled, causing an uneven and variegated design. The loop 1^a terminates as the material is threaded over two flanged guide rolls 7 and 8 mounted on shafts 9 and 10 respectively, said shafts also being supported 80 by the frame 6. The material then proceeds between the embossing roll 11 mounted upon the shaft 12 and the pressure roll 13 mounted upon the shaft 14. After passing about the top of the pressure roll, the embossed material is directed, as shown by the arrows, to the adjoining cooling rolls 15 shown in Fig. 3. The bearings 16 supporting the shaft 12 are mounted upon blocks 17 vertically slidable upon the supporting member 90 85 18. The vertical movement of the blocks 17 is accomplished by means of screws 19, which are threaded in said block and are rotated by means of the worm wheels 20 mounted upon the lower ends of the blocks 17 and the worms 21 mounted upon the shafts 22. The shafts 22 are supported in the frame 6 and are rotatable by means of hand wheels 23. On lugs 24 extending from the lower portion of the blocks 17 are mounted rollers 25 which ride upon the cam wheels 26 pivoted at 27 to the frame 6. A hand lever 28 also pivoted at 27 and fixedly attached to the shaft 27 supporting the cam wheels 26 furnishes a means for lowering the slidable blocks 17 and thereby the roll 11 from contact with the pressure roll 13 without disturbing the pressure adjustment between the rolls. In this manner, after a proper pressure adjustment has been set by 100 105 110

means of the hand wheel 23, if for any reason it should be desired to release instantly the pressure between the embossing and pressure rolls, this hand lever may be used.

5 This quick release is indispensable in case the material is not feeding properly or for any reason has become fouled in the printing or embossing process.

Describing briefly the machine, drive 10 power is furnished from any convenient source (not shown) through the shaft 29 and transmitted to the embossing or printing apparatus through the pinion 30 meshing with the gear 31 mounted upon a shaft 15 32. A gear 33 also mounted upon the shaft 32 meshes through the intermediate gears 34 and 35 with a gear 36 mounted upon the shaft 14 on which is also mounted the pressure roll 13.

20 The pressure roll 13 and the print roll 11 are driven in timed relation by meshing gears 37 and 38 mounted on the shafts 14 and 12 respectively, and on the opposite side of the machine from that on which the

25 principal part of the driving mechanism is mounted. The feed rolls 2 and 3 are driven by means of a belt 39 running over pulleys 40 and 41 mounted on shafts 5 and 14, the upper roll 2 being driven from the lower roll 3 by meshing gears. Beneath the print or embossing roll 11 is positioned a pan 42 in which is placed pigment for printing or water when the roofing is to be embossed.

30 An air pipe 43 equipped with a nozzle device plays a stream of air between the rolls in order to keep them free from foreign substance during the embossing or printing operation. A water jet supply through a pipe 44 plays upon the upper pressure roll

35 and assists in cleaning its surface. This water also prevents the sheet from sticking to the bed roll.

40 One of the important features of the explained embossing or printing mechanism is the fact that this machine is compact and may be inserted in the place of two cooling rolls which are usually positioned vertically in a machine for making waterproof felted substances such as roofing and the like. Heretofore, printing and embossing machines have been constructed to take up quite an extensive floor space and are massive in construction. Also, the machine explained is equipped with flanged guide rolls 45 such as shown at 8 by means of which the roofing sheet is accurately guided between the printing or embossing and pressure rolls.

45 It will be noted also that by threading the roofing sheet in a figure 8 about the guide rolls just prior to its being fed between the print rolls the pressure feed com-

mon to most printing machines is totally eliminated. The elimination of the pressure feed rolls is an important improvement 65 in that a great deal of difficulty caused by uneven feed and tearing of the sheet may be assigned to the pressure feed rolls.

I claim as my invention

1. In a roofing machine the combination 70 with means comprising an embossing roll for imposing a design upon a roofing sheet continuously fed therethrough, feed rolls having guide flanges thereon arranged out of contact and in off-set relation, whereby 75 the material is accurately fed to the design-making means without the use of pressure.

2. In a roofing machine, the combination with a means for imposing a design upon the roofing material, feed rolls adapted to 80 positively feed the material without subjecting it to pressure, and adapted to maintain available at all times an excess of roofing material to prevent strain, or deterioration of the sheet when the design is imposed thereon. 85

3. In a roofing machine the combination with a means for imposing a design upon a roofing sheet, feed rolls comprising a plurality of sets of rolls, the rolls of each set 90 being positioned out of contact, guide flanges on the rolls adjacent the design imposing means, whereby a loop of excess material is maintained between respective sets of feed rolls, whereby differences in rate of travel between the design imposing means and the feeding means are accommodated, and imperfections in the design and deterioration due to strain prevented. 95

4. In a roofing machine the combination 100 with a means for imposing a design on a roofing sheet, comprising a pressure roll and a design roll, feeding means, comprising separate sets of feed rolls in respective sets positioned out of contact, guide flanges on 105 the rolls adjacent the design-imposing means, and vertically movable means for releasing the pressure roll from contact with the design roll, whereby a loop of material may be maintained between the respective sets of feed rolls to compensate for differences in rate of travel. 110

5. In a roofing machine, the combination with a frame, of flanged guide rolls mounted thereon and so arranged that the feed of roofing stock is uniform, a pressure roll contacting with a design imposing roll, means for spraying and scraping the surface of the pressure roll, and means comprising a vertically movable manually controlled means for instantly releasing the pressure roll from contact. 115 120
